UNITED STATES PATENT OFFICE.

JAMES C. ARMOR, OF PITTSFIELD, MASSACHUSETTS.

JAR-OPENER.

1,321,700.

Specification of Letters Patent. Patented Nov. 11, 1919.

Application filed August 29, 1919. Serial No. 320,594.

To all whom it may concern:

Be it known that I, JAMES C. ARMOR, a citizen of the United States, and a resident of Pittsfield, in the county of Berkshire and State of Massachusetts, have invented a new and Improved Jar-Opener, of which the following is a full, clear, and exact description.

This invention relates to improvements in jar openers, an object of the invention being 10 to provide an improved construction of clamp and operating device therefor which causes the effectual release of a cover from the jar no matter how tightly it may be adhering to its gasket.

15 A further object is to provide a device of the character stated in which the clamping member is made with an improved shield, against which the movable jaw of the operating device is adapted to contact and prevent possibility of breaking the neck of the jar.

20 This invention is especially adapted for use in removing jar covers of the spring top type, in other words, those that have covers or tops which are held down upon the gasket by some elastic or other holding means.

25 With these and other objects in view the invention consists in certain novel features of construction, combinations and arrangements of parts, as will be more fully herein-after described and pointed out in the claims.

In the accompanying drawings—

30 Figure 1 is a plan view illustrating my improvements;

Fig. 2 is a view in side elevation; and

Fig. 3 is a detail perspective view of the clamping member 3.

35 Figs. 4 and 5 are detail views illustrating modifications.

This improved device comprises two main parts, namely, a clamp A and an operating device B. The clamp A consists of a relatively thin wire 1 or other suitable flexible 40 material, one end of said wire 1 fixed to a clamping member 2 and the other end of the wire fixed to a clamping member 3.

45 The operating device B comprises two handles 4 and 5 crossed and pivotally connected by a rivet or other suitable pivot 6 and forming relatively short jaws 7 and 8, as shown. Device B is similar to an ordinary pair of pliers in its general operation, and jaw 7 is provided with a headed pin 11 50 adapted to be positioned in any of the series of slots 10 in the clamping member 2, the

said slots being provided with enlarged ends for the entrance of the headed pin 11, as will be readily understood.

The clamping member 3 comprises a 60 curved strip adapted to fit against the neck of the jar to be opened and this strip is formed at one end with an outwardly projecting tongue 12 to which the jaw 8 is pivotally connected by a rivet 14. The wire 1 65 is secured in a perforation 13 in the tongue 12 and in a perforation 9 in the clamping member 2.

In operation, the wire 1 is located under the cover of the jar to be opened and the 70 clamping member 3 against the neck of the jar. When the handles 4 and 5 are forced toward each other, the clamping members 2 and 3 will be moved toward each other to force the wire 1 under the jar cover and dislodge the same from its gasket. During this 75 clamping operation the end of the jaw 7 will ride against the face of the clamping member 3 and be held by said clamping member from contact with the neck of the jar to prevent liability of breaking the jar. The 80 diameter of the clamp can be modified by positioning the pin 11 in any of the slots 10.

To render the device adjustable I may secure enlargements 15 on the wire 1 as shown 85 in Figs. 4 and 5. These enlargements may be either round or square shouldered and formed in any way desired. A slot 16 would be provided in member 3 to receive the wire and by reason of the enlargement 90 15 any desired adjustment might be had to fit any neck of jar or bottle.

Slight changes may be made in the general form and arrangement of the parts described without departing from my invention, and hence I do not limit myself to the precise details set forth, but consider myself at liberty to make such changes and alterations as fairly fall within the spirit and scope of the appended claims. 100

I claim:

1. A device of the character described, comprising two clamping members, a clamping wire connecting the clamping members, a pair of handles pivotally connected and 105 forming relatively short jaws and relatively long hand holds, one of said jaws pivotally connected to one clamping member, the other of said jaws adapted to be connected to any of a series of points on the other clamping member, said first-mentioned clamping member having a curved surface constitut- 110

ing a shield against which one of the jaws is movable during its operation.

2. A device of the character described, comprising two clamping jaws, one of said jaws curved and forming a shield, a laterally projecting tongue on said shield member, a wire connected at one end to the tongue of the shield member and at its other end to the other member, said last-mentioned member having a longitudinal series of slots therein, an operating device comprising a pair of handles pivotally connected and forming relatively short jaws and relatively long hand holds, one of said jaws pivotally connected to the tongue of the shield member, and a headed pin on the other of said jaws adapted to be located in any of the said slots, said pin-carrying jaw adapted at its free end to contact with the shield member when the device is operated.

3. A jar opener comprising a clamp consisting of a relatively thin flexible member, an operating device having movable jaws, one jaw connected to one end of the clamp, the other jaw to the other end of the clamp, 25 a shield being attached to one jaw against which the free end of the other jaw is movable.

4. A jar opener, comprising a clamping wire, a pair of handles pivotally connected 30 and forming relatively short jaws and relatively long hand holds, one of said jaws connected to one end of the clamping wire, the other of said jaws adapted to be connected to any of a series of points on the 35 other end of the clamping wire, a shield attached to one jaw against which the free end of the other jaw is movable.

JAMES C. ARMOR.
